LIQUID ATOMIZER

Frederick W. Lohse, North Attleboro, Mass.

Application July 30, 1935, Serial No. 33,852

7 Claims. (Cl. 299—88)

This invention relates to liquid atomizers and in the particular form herein described is applied to an atomizer of the type convenient for atomizing perfumery, in which it is particularly desirable to have a convenient and reliable means for hermetically sealing the container or bottle when the atomizer is not in use in order to prevent deterioration or evaporation of the expensive liquid content.

It is the object of the present invention to provide a simple, inexpensive and reliable leak proof means capable of adjustment for securing effective atomizing of the liquid to be atomized and with this object in view the invention comprises, generally speaking, the combination, with a bottle closing head provided with a liquid education tube and with a bottle venting orifice, of a reversible atomizing head which in one position serves to receive and atomize the liquid supplied thereto by means of a compressed air passage leading to the atomizing nozzle and, in the other position, forms a complete and reliable means of sealing the closure head against the escape of liquid or the entrance of air to the interior of the bottle, so that the device may be conveniently carried in a handbag or other receptacle without danger of leakage or loss of contents.

This and other features of the invention will be particularly described in the following specification and will be defined in the claims hereto annexed.

A simple and convenient embodiment of the principles of this invention is illustrated in the accompanying drawing, in which

Fig. 1 is a front elevation of the complete assemblage of atomizer and container viewed in the direction of the axis of the atomizing nozzle.

Fig. 2 is an elevation of the complete atomizer as viewed at right angles to the plane of Fig. 1.

Fig. 3 is an enlarged view in vertical central section intersecting the axis of the discharge nozzle.

Fig. 4 is a similar view showing the atomizer head adjusted to inverted or sealing position to seal the stopper head outlets against the escape of liquid or entrance of air.

Fig. 5 is a vertical section on plane 5—5 of Fig. 3 showing the detail of atomizing nozzle.

In the practice of the invention as herein described and illustrated in the drawing, the liquid container or bottle 1 may be of any suitable form provided with an open neck for connecting the atomizing stopper and head in any suitable manner, as by means of a tight fitting coupling mem-

ber 2, which is internally screw threaded to receive the externally threaded attaching nipple of the closure head 3, which is provided with a central liquid discharge passage 4 which is in constant communication with the liquid through the medium of the liquid eduction tube 5, which projects downward into the body of liquid. The closure head 3 is also provided with an off-center bottle venting passage 6. The closure head or stopper 3 has an upward tubular extension 3a which is provided with a transverse diametrical slot extending to its top in order to permit the insertion of the atomizing head hereinafter described. The liquid discharge passage 4 is formed with a smooth annular upper edge 15 providing a sealing seat and at a sufficient distance therefrom is provided a larger sealing seat formed, in this case, by means of a gasket or washer 13 dimensioned to include within it both the liquid discharge passage 4 and the off-center vent passage 6.

The atomizing and sealing head, in this case, comprises a cylindrical plug or head 9 which, in the position indicated in Fig. 3 for atomizing liquid, has a flat top and a convex bottom concentric with the liquid discharge passage 4. Said plug 9 is provided with a transverse internally threaded bore 10, which receives liquid from the liquid discharge passage 4 in the stopper through a vertical central passage 10a arranged on the central axis of the plug or head. In the discharge end of the transverse passage 10 is secured an atomizing nozzle 11 having a discharge orifice 11a and inside of this atomizing nozzle extends the reduced end of a compressed air tube 12 arranged, as shown in Fig. 5, to leave passages between its exterior and the inside of the discharge nozzle 11 sufficient to allow the flow of liquid through the atomizing nozzle caused by the partial vacuum produced by the passage of the compressed air through the air supply tube 12 and out through the discharge orifice 11a on the well known exhaust or vacuum principle.

The compressed air or aspiratory tube 12 is connected with any suitable source of compressed air, such as the usual air compressing bulb 20.

It is of course necessary, in order to secure effective aspiration of the liquid, to form a tight joint between the lower end of the atomizing head 9 and the seat surrounding the discharge passage 4 in the stopper head 3. Accordingly, the lower end of the atomizing head 9 is of convex form, preferably of conical form

concentric with the liquid passage 10^a, so that the convex or conical surface of this part of the atomizing head tightly engages the annular seat surrounding the liquid discharge passage 4.

5 This tight joint is effected by the clamping nut 8, which is internally threaded to engage the exterior thread of the upward tubular extension 3^a of the stopper and which is provided with a centrally recessed boss 8^a adapted to exert a strong 10 thrust against the upper end of the atomizing head 9 when the clamping nut is screwed down against the same. It will be understood that the inner wall of the tubular extension 3^a is dimensioned to snugly receive and retain the cylindrical atomizing head 9.

Obviously, when the nut 8 is removed the atomizing head can be inserted into the tubular extension 3^a of the stopper with its lower convex end bearing against the annular seat aforesaid, 20 while the clamping action of the nut insures a tight joint in order to permit effective exhausting of the liquid through the atomizing nozzle.

When it is desired to seal the atomizer against leakage the nut or threaded cap 8 is removed, the 25 atomizing head 9 is lifted from its seat, turned upside down or reversed and is inserted in its inverted position into the tubular extension until its then lower end engages the annular sealing seat 13. The clamping nut is then screwed down 30 to force the atomizer head tightly against the outer sealing seat 13 and thus escape of liquid through either the discharge passage 4 or the bottle venting passage 6 is positively prevented.

The construction is very inexpensive as it calls 35 for no exacting precision of parts, while the sealing of the bottle as well as the establishing of an effective joint between the liquid passages of the atomizing head and the liquid eduction tube is perfectly effected, while at the same time in 40 atomizing position the vent orifice opening outside that joint into the tubular slotted extension perfectly performs its function of supplying air to the interior of the bottle as the liquid is exhausted. The whole construction is self-contained and depends merely upon the reversing 45 adjustment of the atomizer head, while all joints, either for connecting the liquid passages or for sealing the stopper against the escape of liquid, are absolutely leak proof due to the tightness of 50 the joints secured through the clamping nut.

What I claim is:

1. In a leak proof atomizer the combination of 55 a bottle stopper provided with liquid discharge and air venting passages, an atomizing head having liquid discharge and compressed air passages leading to an atomizing nozzle and being removable and reversible end for end, said head in one position of adjustment providing a tight communicating connection between the liquid discharge passages of the stopper and of the head and when adjusted to an inverted position providing a stopper sealing joint preventing leakage of liquid through said stopper.

2. In a leak proof atomizer the combination 60 of a bottle stopper provided with liquid discharge and air venting passages, an atomizing head having liquid discharge and compressed air passages leading to an atomizing nozzle, said head in one position of adjustment providing a tight communicating connection between the liquid discharge passages of the stopper and of the head and when removed and reinserted in reversible end for end position providing a stopper sealing joint preventing leakage of liquid through said 65 stopper, and means for clamping said head when

in either position against the stopper to insure tight joints.

3. A leak proof atomizing stopper embracing 70 in its construction a bottle stopper adapted for attachment to a liquid container and provided with separate liquid discharge and air venting passages and having concentric annular seats, the inner of which includes the liquid discharge passage, the outer of which includes both said 10 passages, a separate atomizing head provided with liquid-discharge and air-venting passages, one end of which, when disposed in lowermost position, engages the inner seat to form a communicating joint between the liquid discharge 15 passages, the other end of said head being formed to engage the outer seat when in lowermost position, and means for tightly clamping said head in either position of adjustment against the appropriate seat to establish in the one case a tight joint connection for the flow of liquid through 20 the atomizer and in the other case a leak proof seal for both stopper passages preventing the escape of liquid through the stopper.

4. In a device of the class described, the combination of a bottle stopper provided with separate liquid discharge and air venting passages and having a tubular extension interrupted by a transverse slot, an atomizing head having a transverse bore carrying at one end an atomizing nozzle and at the other end an air injecting tube, 30 one end of said head being formed with a convex surface converging upon a central passage affording communication between the liquid passage in the stopper and the liquid passage in the head, the other end of said head being provided with a sealing surface arranged when the head is inverted to seal the stopper against the escape of liquid through either of the passages.

5. In a device of the class described, the combination of a bottle stopper provided with separate liquid discharge and air venting passages and having a transversely slotted tubular upward extension, an atomizing head adapted to be inserted in said tubular extension and having an atomizing nozzle projecting through one side 40 of the slot, and a compressed air tube projecting through the opposite side of the slot, said head being provided with a vertical central liquid passage for conducting liquid to the atomizing nozzle when the head is in one position of adjustment and when in inverted position of adjustment 45 serving as a sealing closure to prevent escape of liquid through the stopper, and a clamping nut having threaded engagement with the stopper to force the atomizing head in either position of adjustment tightly against said stopper.

6. A device of the class described embracing 55 a bottle stopper provided with separate liquid discharge and air venting passages and having a vertically slotted tubular extension, an atomizing head having an atomizing nozzle arranged for insertion in one vertical slot and having communication through the lower end of said head with the liquid discharge passage in the stopper and having also communication with an air injecting tube arranged for insertion in another vertical slot, the other end of said head being imperforate and forming when the head is inverted a closure preventing the escape of liquid through either stopper passage, and means for 60 firmly seating said head when in either position of adjustment against the lower portion of the stopper.

7. A device of the class described embracing 65 a bottle stopper provided with liquid discharge

and air venting passages, a reversible atomizing head removable from and reversibly insertable in the upper part of said stopper in position to receive from the liquid discharge passage in the stopper a supply of liquid and deliver it in an atomized spray when in one position of adjustment and when in its reverse position of adjust-

ment preventing the escape of liquid through the passages in the stopper, and screw threaded means for forcing said reversible head into firm engagement with said stopper when said head is inserted in atomizing position or in its reversed sealing position. 5
